FUEL FEEDING APPARATUS

Filed June 14, 1937

UNITED STATES PATENT OFFICE

2,166,850

FUEL-FEEDING APPARATUS

Frederick T. Snyder, Brookline, Mass., assignor to Fuel Research Development Corporation, Boston, Mass., a corporation of Massachusetts

Application June 14, 1937, Serial No. 148,166

1. Claim. (Cl. 48—86)

This invention relates to apparatus for feeding both liquid and solid fuels to a gas generator or retort, more particularly when of the blast furnace type.

5 It is the general object of my invention to provide improved apparatus for feeding coal or coke or other solid or semi-solid fuels to the top of a gas generator, and for feeding oil or gaseous fuel to a point within the fuel mass.

10 A further object of my invention is to provide a heat-insulated oil feeding device for such purposes, together with means for conveniently determining the elevation of the point of oil delivery.

15 My invention further relates to arrangements and combinations of parts which will be herein-after described and more particularly pointed out in the appended claim.

A preferred form of the invention is shown in 20 the drawing, in which

Fig. 1 is a sectional side elevation of the upper part of a generator, with my improved feeding apparatus mounted thereon;

25 Fig. 2 is an elevation of the feeding apparatus, partially broken away and looking in the direction of the arrow 2 in Fig. 1;

Fig. 3 is a plan view of a cover plate, looking in the direction of the arrow 3 in Fig. 1;

30 Fig. 4 is a plan view of a packing device, looking in the direction of the arrow 4 in Fig. 1;

Fig. 5 is a sectional side elevation of the packing device, taken along the line 5—5 in Fig. 4; and

35 Fig. 6 is an enlarged sectional elevation of the lower end portion of the oil feeding device.

Referring to the drawing, I have shown a portion of a furnace or generator 10 having a reaction chamber or stack 11 and having an enlarged upper end portion 12 provided with a gas 40 outlet 14. A cover plate 15 closes the upper end of the generator, and a casing or hopper 16 is mounted in an axial opening in the cover plate 15 and may be secured in position by clamping bolts 17.

45 The upper end of the casing or hopper 16 is normally closed by a cover 20 having concentric ribs 21 on its lower face which provide an annular groove for receipt of a wick or packing 22.

Clamping bolts 23 are pivoted at 24 on lugs 25 50 fixed to the casing 16, and these bolts 23 may be swung upward into notches 26 in the cover 20. Wing or handle nuts 27 are provided for clamping the cover 20 firmly on the casing 16.

55 The cover 20 is provided with an axial opening 28, which opening is surrounded on the upper

face of the cover by a flange having a deep annular recess 29 which is partially filled with mercury, for a purpose to be described.

An oil feeding device 30 extends axially through the hopper or casing 16 and extends loosely 5 through the opening 28 in the cover 20. This oil feeding device comprises a feed pipe 32 provided at its lower end with a nut or head 33 which supports a tube 34, formed of fire-clay or other heat-insulating and heat-resisting material.

This fire-clay tube 34 extends to a point above the burning fuel mass, as indicated in Fig. 1, and loosely supports a conical metal collar 35, which in turn supports the lower end of an outer metal pipe 36, substantially spaced from the oil 15 feed pipe 32. This pipe 36 extends upward through the coal feeding hopper, and the space between the two pipes 32 and 36 is filled and firmly packed with asbestos or other suitable heat-insulating material. 20

While this annular space between the pipes is being filled, the pipes 32 and 36 may be held concentric by three adjusting screws 37 (Fig. 1) which are threaded in the outer pipe 36 and which may be removed after the space between 25 the pipes is filled. The upper end of the pipe 36 extends loosely through an opening 39 in a suitable support 40 and may be centered and secured therein by a plurality of set-screws 41.

The upper end of the pipe 32 is threaded into 30 a cap 42 having an oil inlet 43. A washer 44 is loosely mounted on the pipe 32 below the cap 42 and rests upon the upper end of a two-part spacing sleeve 45, which in turn rests upon the support 40. The sleeve 45, washer 44 and cap 42 35 thus effectively support the oil feeding device 30 and determine its vertical position, independently of the set screws 41. Preferably a plurality of two-part sleeves 45 of different lengths will be provided, so that the oil feeding device 30 may 40 be positioned at different selected elevations.

A collar 50 (Figs. 1 and 5) is loosely mounted on the outer pipe 36 and is provided with a wick packing 51 held in position by a plate 52. A sleeve 53 is mounted on the collar 50 and extends 45 downward therefrom into the mercury in the annular groove 29. The groove 29 is of substantial width, so that if the oil feeding device 30 is slightly crooked or out of alignment, it will nevertheless pass freely through the opening 28 and 50 will be effectively sealed by the mercury in the groove 29.

Whenever it is necessary to remove the oil feeding device 30, this may be easily done by loosening the set-screws 41, after which the device 30 55

may be lifted out of the generator. The collar 50 may remain in place or may be removed with the device 30, according to the tightness of the wick packing 51.

5 The lower end of the casing or hopper 16 is normally closed by a bell 60 having an axial opening 61 to loosely receive the oil feed device 30. A collar 62 is slideable on the device 30 and rests on a flange 64 extending upward from the bell 60, 10 thus substantially sealing the opening around the pipe 36.

The bell 60 is suspended by links 65, springs 66 and links 67 from a pair of arms 68 mounted on a rock shaft 69 pivotally supported in an enlarged 15 side portion 70 of the casing 16. A weight arm 71 is secured to the rock shaft 69 outside of the casing 16 and is provided with a weight W which may be adjusted along the arm 71 and which may be secured in any desired position.

20 When coal, coke or other solid or semi-solid fuel is to be fed to the generator, the cover 20 is unclamped and is slid upward along the oil feed device 30 a sufficient distance to provide access to the top of the hopper 16, within which 25 the fuel charge is then placed. The cover 20 is then reclamped in normal position and the arm 71 is swung upward, thus lowering the bell 60 and allowing the fuel charge to escape into the furnace, after which the bell is again raised and 30 positioned by the weight W.

It is thus possible to feed solid fuel to the hopper 16 without disturbing the oil feeding device

30 or changing its adjustment, and without escape of gas.

The vertical working position of the oil feeding device may be varied by inserting different sleeves 45 under the washer 44 and cap 42. If the lower 5 end of the pipe 32 should become partially closed by soot or coke, the entire oil feeding device 30 could be removed as previously described.

The heat-insulating of the oil feed pipe is of particular importance in gas generators which 10 operate at relatively high temperatures, as it prevents the cracking of the oil within the feed pipe which might otherwise occur with production of soot or tar which would clog the feed pipe.

In the claim, reference to oil feed will be understood to include also vapor feed.

Having thus described my invention and the advantages thereof, I do not wish to be limited to the details herein disclosed, otherwise than as set forth in the claim, but what I claim is:

20 In a gas generator having a stack with a vertical central passage forming a gas generating retort and having means to feed solid fuel to the upper end of said passage, that improvement in an oil feeding device for said gas generator which 25 comprises an oil feed pipe extending downward a substantial distance into the fuel mass, a fire-clay casing for the lower part of said feed pipe, an outer pipe mounted above said casing and supported thereby, and a filling of heat-insulating 30 material between said feed pipe and said outer pipe.

FREDERICK T. SNYDER.
